CLAIM

I claim the ornamental design for a “spatula with thermometer probe,” as shown and described.

DESCRIPTION

FIG. 1 is a top, front, perspective view of a spatula with a thermometer probe showing my new design;

FIG. 2 is a front view thereof;

FIG. 3 is a rear view thereof;

FIG. 4 is a top view thereof;

FIG. 5 is a bottom view thereof;

FIG. 6 is a left end view thereof; and,

FIG. 7 is a right end view thereof.

The broken lines in the drawings represent portions of the spatula with a meat thermometer which form no part of the claimed design.
